UNITED STATES PATENT OFFICE

144,984

DESIGN FOR A TOY FIGURE BLOCK

Frederick William Plumer, Wilmette, Ill., assignor of one-half to Florence Rosenberg, Chicago, Ill.

Application July 11, 1945, Serial No. 120,636

Term of patent 14 years

(Cl. D34—15)

To all whom it may concern:

Be it known that I, Frederick William Plumer, a citizen of the United States, residing at Wilmette, in the county of Cook and State of Illinois, have invented a new, original, and ornamental Design for a Toy Figure Block, of which the following is a specification, reference being had to the accompanying drawing, forming part thereof.

In the drawing, Figure 1 is a front elevational view of a toy figure block, showing my new design; Figure 2 is a side elevational view of the same; and Figure 3 is an enlarged perspective view of the same.

The back of the toy figure block is conventionally plain.

The dominant feature of my design resides in the portion shown in solid lines.

I claim:

The ornamental design for a toy figure block, substantially as shown and described.

FREDERICK WILLIAM PLUMER.
